COVER ARRANGEMENT FOR BUSINESS
MACHINESGito Winter and Hans Eichemeyer, Wilhelmshaven,
Germany, assignors to Olympia Werke AG., Wilhelmshaven,
Germany

Filed Mar. 6, 1962, Ser. No. 177,834

Claims priority, application Germany Mar. 6, 1961
8 Claims. (Cl. 45—68.1)

The present invention concerns business machines e.g. typewriters, equipped with a cover member which is tiltably and removably mounted on the machine frame and serves to cover or to protect certain mechanical components of the business machine.

In conventional arrangements of this type the cover member is tiltably supported with pivot pins in resilient bearing devices which exert a clamping action on the pivot pins so that the cover member may be removed by tilting it upward and lifting its pivot pins out of engagement with the bearing devices. On the other hand, for re-installing the cover member the pivot pins have to be first pushed into engagement position with the bearing devices whereafter the cover member is tilted down into its normal position. These conventional devices suffer from the drawback that by careless handling during re-installing the cover member the elastic members of the bearing devices may be bent or damaged so that the cover member cannot assume its accurate and proper position. In addition, the downward direction of inserting the pivot pins into the bearing devices makes it necessary in most cases to move certain portions of the business machine, e.g. the carriage of a typewriter, into such a position that it does interfere with the handling of the cover, both when the latter is to be removed and when it is to be re-installed in place. Moreover, the danger exists also that during the re-installation of the cover certain portions of the business machine, e.g. the platen of a typewriter, is damaged. To reduce this danger it may be necessary to provide for special guide means for guiding the cover into a position in which its pivot pins can engage the bearing devices.

It is therefore one object of this invention to provide for an arrangement which eliminates the above-mentioned disadvantages.

It is another object of this invention to provide for an arrangement of the type set forth which is considerably simpler and more reliable than conventional arrangements.

With above objects in view the invention includes an arrangement for detachably securing a cover member in predetermined position on a business machine frame member, comprising, in combination, on the inner faces of the lateral side walls of the machine frame member and of the cover member, respectively, a pair of separable hinge means, each hinge means comprising a first member including a pivot portion and attached to the respective side wall of one of the machine frame and cover members, and a second member attached to the respective side wall of the other one of the machine frame and cover members and including a bearing portion engageable with said pivot portion, so that, when said portions of both hinge means are in engagement, the cover member is tiltably about an axis connecting said pivot portions; and on the inner faces of the walls of the machine frame member and of the cover member, respectively, at points spaced from the location of said hinge means, a pair of locking means, each locking means comprising a catch member attached to the respective wall of one of the machine frame and cover members and a resilient latch member mounted on the respective wall of the other one of said machine frame and cover members and being

2

engageable with said catch member, said hinge means and said locking means being so arranged in relation to each other that when said portions of said hinge means are in engagement and said latch and catch members are in engagement the cover member is secured in predetermined position on said machine frame member.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

15 FIG. 1 is a perspective view illustrating the right hand portion of a business machine frame and of a corresponding cover member including one set of hinge and locking means according to the invention in disengaged position; and

20 FIG. 2 is an elevational view of the members of FIG. 1 in engaged position.

In the illustrated embodiment a separable hinge structure is illustrated which comprises a first member 2 attached for instance by spot welding to a selected point of the inner face of one side wall 1a of the machine frame 1, and a second member 5 attached in the same manner to the inner face of the corresponding side wall 4a of a cover member 4. The member 2 includes an inwardly offset upright portion 2a which carries a pivot pin 3. Instead of attaching a pivot pin 3 to the bracket 2 an equivalent pivot portion may be formed integrally from the material of the bracket 2. The pivot portion of the member 2 projects toward the interior of the machine. The corresponding member 2 mounted on the opposite side wall of the machine frame is so located that the line connecting the pivot portions 3 of the two members 2 constitutes the axis of the desired tilting movement of the cover 4, preferably parallel with the front edge of the machine, as will be described further below. A forward extension 2b of the portion 2a is slightly bent outwardly so as to act as a guide for the member 5 when the two hinge members 2 and 5 are to be brought into engagement.

The second member 5 has an inwardly offset portion 5a extending in rearward direction and perpendicular to the above-mentioned tilting axis. The portion 5a has a V-shaped cutout adapted to straddle the pivot portion 3. The free end of the portion 5a is slightly bent inwardly so as to be adapted to meet the portion 2b of the member 2 when the cover 4 is being installed in place. The member 5 further includes an inwardly projecting extension 5b covered with elastic material 6, e.g. consisting of a piece of tubular elastomeric material which is so positioned that upon installation of the cover 4 in place it rests on the upper edge 1b of the machine frame 1 as shown in FIG. 2.

The locking arrangement according to the invention, mounted at a certain distance from the above-described hinge arrangement, comprises a latch member 7 mounted on the inner face of the side wall of the cover member 4, and a catch member 10 mounted in corresponding position on the side wall 1a of the machine frame 1. The latch and catch members 7 and 10 may also be attached to the frame and cover members, respectively, by spot welding.

65 The catch member 10 has two upwardly extending portions 10a and 10b. The portion 10a is formed so as to extend in a plane substantially perpendicular to the side wall 1a of the frame and its upper end is slightly bent in forward direction so as to act as a guide for the forward edge of the latch member 7 when the portions of the locking arrangement are moved into engagement, as will be

described further below. The other portion $10b$ is formed to a V-shape as shown at $10c$ to act as a catch, and the upper free end of the portion $10c$ is slightly bent inwardly at $10d$ in order to facilitate the engagement of the resilient latch portion 9 with the catch portion $10c$ as will be described further below. It is to be noted that the portions $10a$ and $10b$ do not have to be resilient but are preferably rigid.

The latch member 7 has three portions $7a$, $7b$ and $7c$ projecting inwardly of the machine and substantially horizontally. The portion $7a$ is provided with a piece of elastic material 8 , preferably a tubular piece of elastomeric material. It serves to cushion the member 7 on the upper edge $1b$ of the frame when the locking arrangement is in engaged position as shown in FIG. 2. A resilient latch member 9 consisting of a coiled tension spring is mounted between the portions $7b$ and $7c$, for instance by engagement of its end hooks into holes or notches provided in the portions $7b$ and $7c$, respectively. The spring 9 is so positioned that when the cover with the latch member 7 is moved downwardly it will resiliently engage the V-shaped portion $10c$ of the catch member 10 .

In operation the arrangement according to the invention functions as follows:

When the cover member 4 is to be installed in the desired position, as shown in FIG. 2, on the machine frame member 1 , then the cover member 4 is to be moved, with the latch member 7 slightly lifted above the catch member 10 , in substantially horizontal direction in the direction from front to the rear of the machine (from right to left as seen in FIG. 2) in such a manner that the V-shaped cutouts of the two hinge portions $5a$ straddle and engage the corresponding pivot members 3 . During this movement and before such engagement the bent portions $2b$ and $5a$ meeting each other assist in producing the desired transverse alignment of the hinge portions and therefore also of the cover 4 with the machine frame 1 . As soon as the hinge portions are in engagement with each other, the front end of the cover 4 may be tilted in downward direction so that the springs 9 of the two latch members 7 snap into the respective portions $10c$ of the catch members 10 . It is clear that the springs 9 will yield slightly when they engage the upper portions $10d$ of the respective catch members 10 before snapping into engagement. During the engaging movement just described the forward edges of the latch members 7 are likely to engage the forward bent upper ends of the portions $10a$ of the catch members 10 so that a final push is exerted on the cover 4 whereby the hinge portions $5a$ and pivot portions 3 are forced into intimate engagement and the accurate desired positioning of the cover 4 on the machine frame 1 is assured. At the same time the elastic cushion members 6 and 8 are pressed on the upper edges $1b$ of the machine frame so that the cover is now firmly held in the desired position.

When the cover 4 is to be removed the above described operations are carried out in reverse, i.e. first the front end of the cover is slightly lifted so as to disengage the catch member from the latch member whereafter the cover can be withdrawn in forward direction so as to disengage the hinge portions $5a$ from the pivot portions 3 .

It should be noted that the above-described embodiment is only one example of carrying out the invention. For instance, the latch member 7 could be mounted in upside-down position on the side wall $1a$ of the machine frame while the catch member 10 would be mounted in upside-down position on the side wall $4a$ of the cover 4 . Similarly, the hinge portions 2 and 5 could be exchanged against each other. Only in this case the V-shaped cutout of the portion $5a$ which in the illustrated example opens toward the rear would have to be arranged so that it opens toward the front of the machine so that the pivot portion 3 carried by the cover can be moved in direction toward the rear into the recess of the portion $5a$.

It should be noted further that the entire arrangement

according to the invention does not comprise any springs of the blade type which are likely to lose their strength or to be bent or distorted during continuous use. No such danger exists for a coiled spring 9 used in the arrangement 5 according to the invention as a resilient latch member.

Where space conditions permit the locking means 7 , 10 may be mounted along the front walls of the machine frame and cover members.

It will be understood that each of the elements described 10 above, or two or more together, may also find a useful application in other types of an arrangement for detachably securing a cover member on a business machine frame differing from the types described above.

While the invention has been illustrated and described 15 as embodied in an arrangement for detachably securing a cover member on a business machine frame and comprising separable hinge means and resilient locking means, it is not intended to be limited to the details shown, since various modifications and structural changes may be made 20 without departing in any way from the spirit of the present invention.

Without further analysis, the foregoing will so fully reveal the gist of the present invention that others can by applying current knowledge readily adapt it for various 25 applications without omitting features that, from the standpoint of prior art, fairly constitute essential characteristics of the generic or specific aspects of this invention and, therefore, such adaptations should and are intended to be comprehended within the meaning and range of 30 equivalence of the following claims.

What is claimed as new and desired to be secured by Letters Patent is:

1. An arrangement for detachably securing a cover member in predetermined position of being superimposed on a business machine frame member, comprising, in combination, on the inner faces of the lateral side walls of the machine frame member and of the cover member, respectively, a pair of separable hinge means, each hinge means comprising a first member including a pivot portion and attached to the respective side wall of one of the machine frame and cover members, and a second member attached to the respective side wall of the other one of the machine frame and cover members and including a bearing portion disengageable from and engageable with said pivot portion so that, when said portions of both hinge means are in engagement, the cover member is tiltable about an axis connecting said pivot portions, said hinge means being so constructed and arranged that, when said cover member is in slightly tilted up position relative to a position of being superimposed on said frame member, said pivot and bearing portions are engageable with, and disengageable from, each other by substantially horizontal rearward and forward movement, respectively, of said cover member relative to said frame member; stop means mounted on said frame and cover members and arranged for preventing movement of said cover member relative to said frame member when the former is superimposed on the latter but permitting movement of said cover member in said substantially horizontal direction when the latter is in slightly tilted up position relative to said superimposed position so as to permit in this position disengagement and engagement of said separable hinge means by such substantially horizontal movement of said cover member; and locking means mounted on said frame member and the cover member, respectively, and releasably holding said cover member on said frame member when in said superimposed position in which forward movement of said cover member is blocked by said stop means.
2. An arrangement for detachably securing a cover member in predetermined position of being superimposed on a business machine frame member, comprising, in combination, on the inner faces of the lateral side walls of the machine frame member and of the cover member, respectively, a pair of separable hinge means, each hinge

means comprising a first member including a pivot portion and attached to the respective side wall of one of the machine frame and cover members, and a second member attached to the respective side wall of the other one of the machine frame and cover members and including a bearing portion disengageable from and engageable with said pivot portion, so that, when said portions of both hinge means are in engagement, the cover member is tiltable about an axis connecting said pivot portions, said hinge means being so constructed and arranged that, when said cover member is in a slightly tilted up position relative to a position of being superimposed on said frame member, said pivot and bearing portions are engageable with, and disengageable from, each other by substantially horizontal rearward and forward movement, respectively, of said cover member relative to said frame member; stop means mounted on said frame and cover members and arranged for preventing movement of said cover member relative to said frame member when the former is superimposed on the latter but permitting movement of said cover member in said substantially horizontal direction when the latter is in slightly tilted up position relative to said superimposed position so as to permit in this position disengagement and engagement of said separable hinge means by such substantially horizontal movement of said cover member; and locking means mounted on said frame member and cover member, respectively, at points spaced from the location of said hinge means, said locking means comprising a catch member attached to the respective wall of one of the machine frame and cover members and a resilient latch member mounted on the respective wall of the other one of said machine frame and cover members and comprising a coiled spring member held in tensioned condition and being engageable with said catch member, said hinge means and said locking means being so arranged in relation to each other that when said portions of said hinge means are in engagement and said latch and catch members are in engagement the cover member is secured in superimposed position on said machine frame member.

3. An arrangement for detachably securing a cover member in predetermined position of being superimposed on a business machine frame member, comprising, in combination, on the inner faces of the lateral side walls of the machine frame member and of the cover member, respectively, a pair of separable hinge means, each hinge means comprising a first member including a pivot portion and attached to the respective side wall of one of the machine frame and cover members, and a second member attached to the respective side wall of the other one of the machine frame and cover members and including a bearing portion disengageable from and engageable with said pivot portion, so that, when said portions of both hinge means are in engagement, the cover member is tiltable about an axis connecting said pivot portions, said hinge means being so constructed and arranged that, when said cover member is in a slightly tilted up position relative to a position of being superimposed on said frame member, said pivot and bearing portions are engageable with, and disengageable from, each other by substantially horizontal rearward and forward movement, respectively, of said cover member relative to said frame

5 member; stop means mounted on said frame and cover members and arranged for preventing movement of said cover member relative to said frame member when the former is superimposed on the latter but permitting movement of said cover member in said substantially horizontal direction when the latter is in slightly tilted up position relative to said superimposed position so as to permit in this position disengagement and engagement of said separable hinge means by such substantially horizontal movement of said cover member; and locking means mounted on said lateral side walls of the machine frame member and of the cover member, respectively, at points spaced from the location of said hinge means, said locking means comprising a catch member attached to the respective lateral side wall of one of the machine frame and cover members and a latch member mounted on the respective lateral side wall of the other one of said machine frame and cover members and comprising a coiled spring member held in tensioned condition and being engageable with said catch member, said hinge means and said locking means being so arranged in relation to each other that when said portions of said hinge means are in engagement and said latch and catch members are in engagement the cover member is secured in superimposed position on said machine frame member.

20 4. An arrangement as claimed in claim 2, wherein said second portion of said hinge means is a bracket having a forked portion defining a recess extending in the longitudinal direction of said lateral sidewalls and adapted to straddle said pivot portion of said first portion of the respective hinge means.

25 5. An arrangement as claimed in claim 4, wherein said latch member is a bracket including means for holding said coiled spring in a position wherein its longitudinal axis extends substantially in the longitudinal direction of said lateral side walls.

30 40 6. An arrangement as claimed in claim 5, wherein said catch member is a rigid bracket having a portion extending toward said latch member and being formed with a recessed portion positioned and adapted to be engaged by said coiled spring.

35 45 7. An arrangement as claimed in claim 6, wherein said catch member has a second portion including guide means for engaging a portion of said bracket of said latch member and for forcing said hinge means into firm engagement when said locking means are moved into engaged position.

50 8. An arrangement as claimed in claim 7, wherein said brackets of said hinge means and of said locking means are provided with elastic cushioning means positioned and adapted to resiliently engage corresponding portions of said machine frame member.
